United States Patent Office

Des. 217,507
Patented May 5, 1970

217,507

METAL FOIL OR SIMILAR ARTICLE

John E. Stengel, Bon Air, Va., assignor to Rubbermaid Incorporated, Wooster, Ohio, a corporation of Ohio

Filed July 31, 1969, Ser. No. 18,499

Term of patent 14 years

Int. Cl. D5—03

U.S. Cl. D59—2

The figure is a plan view of a metal foil showing my new design. The unit shown repeats in a corner relationship with the left side matching the right and the top side matching the bottom side.

I claim:

The ornamental design for a metal foil or similar article, substantially as shown and described.
